(57) **CLAIM**

The ornamental design for a bunion corrector as shown and described.

DESCRIPTION

FIG. 1 is a front, right and top perspective view of a bunion corrector, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 2; and,

FIG. 10 is a perspective view of the bunion corrector of FIG. 1, shown in condition of use for clarity of disclosure.

In the drawings, the broken lines on the bunion corrector depict portions that form no part of the claimed design. The broken lines showing a human foot in FIG. 10 depict environmental structure that forms no part of the claimed design. All broken lines form no part of the claim.

1 Claim, 10 Drawing Sheets
